UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

COMPENSATING DEVICE FOR OIL-PUMP COUNTERS, ETC.

Application filed March 10, 1924. Serial No. 698,092.

To all whom it may concern:

Be it known that I, CURTIS HUSSEY VEEDER, a citizen of the United States, residing in Hartford, in the State of Connecticut, 5 have invented certain new and useful Improvements in Compensating Devices for Oil-Pump Counters, Etc., of which the following is a specification, reference being had to the accompanying drawing, forming a 10 part hereof.

In the application of Harold J. Williams, Serial No. 679,918, filed December 11, 1923, there is shown and described a device to compensate for defective or inaccurate operation 15 of a pump in the delivery of gasoline and other liquids so that the registering or counting mechanism shall at all times indicate or register accurately the volume of liquid delivered, regardless of the inaccuracy 20 in the pump and regardless of the extent of movement of the pump piston, that is, whether the piston is moved through a whole stroke or through part of a stroke. In that device the driven member, in operative relation 25 with the registering or counting mechanism, receives from the driving member, which is in operative relation with the pump, a helical motion so that the compensation in the movement of the registering 30 or counting mechanism shall be proportional to the length of stroke of the pump. In the embodiment of the invention illustrated in said application the driver has a series of slots each one of which has one side at a 35 right angle to the direction of movement of the slotted member and the other side inclined, the inclined sides of the several slots being inclined at different angles. The driven member has a pin which may be 40 engaged in one or another of such slots and has a movement with the driver, in the direction of its movement, and a movement which is longitudinal with respect to the driver. The engagement of the pin of the 45 driven member in a slot which has one side at a right angle to the direction of movement of the driver and the other side inclined, affords opportunity for lost motion or backlash between the driver and the 50 driven member which might be taken advantage of by a dishonest employee to effect what is called "milking" of the pump, by which delivery of gasoline is effected without accurate registration of the volume

delivered. The object of the present invention is to prevent such backlash between the driver and the driven member and therefore to prevent the milking of the pump. This object is accomplished by inclining both sides of each slot in parallelism, the pin of the driving member fitting closely in such slot so that there can be practically no lost motion between the two members. The invention will be more fully explained herein-after with reference to the accompanying 55 drawings in which it is illustrated, and in which—

Figure 1 is a view in longitudinal central section, partly broken out, showing a counter or register and the compensating devices 70 through which the same is driven.

Figure 2 is a detail view in section on the plane indicated by the broken line 2—2 of Figure 1, looking in the direction of the 75 arrows.

Figure 3 is a detail view in section on the plane indicated by the broken line 3—3 of Figure 1, looking in the direction of the 75 arrows.

Figure 4 is a detail view of the compensating devices, partly in elevation and partly in section.

Figure 5 is a detail view of the driving shell or cup and its several slots as if laid out, with the several positions of the driving 80 pin indicated.

Figure 6 is a detail view in section on the plane indicated by the broken line 6—6 of Figure 1, looking in the direction of the 85 arrows.

Figure 7 is a detail view of the friction clutch in section on the plane indicated by the broken line 7—7 of Figure 1, looking in the direction of the 90 arrows.

It is assumed that the shell or cup *a*, 95 shown particularly in Figures 1, 2, 4 and 5, is in operative relation with some part of the pump operating mechanism so that it receives therewith a rotary oscillating movement and becomes the driver for the counter 100 through the devices to be described. The cup or shell *a*, in the present instance, is shown as formed in its peripheral wall with four slots *a*¹, *a*², *a*³, *a*⁴, with parallel sides, the first slot *a*¹ being at a right angle with the direction of movement of the slotted member while the successive slots are inclined at successively increasing angles. 105

- With one or another of the slots a^1, a^2, a^3, a^4 , to be selected in accordance with a test performance of the pump, there is engaged a pin b which is carried by a sleeve nut b' , the latter being mounted on the threaded portion c of a shaft c' , which may be the supporting shaft for the number wheels of the counter or register, being itself held from rotation as by a key c^2 .
- 10 It will be observed that if the pin b is in engagement with the slot a^1 , which is at a right angle with the direction of movement with the slotted member, indicated by the arrow thereon, the sleeve b' will have the same angular movement as the cup or shell a , although it moves at the same time longitudinally with respect to the shaft c' . If, however, the pin b is engaged with one of the slots a^2, a^3 or a^4 , which are successively inclined, as indicated, the pin b moving longitudinally with respect to the shaft c' , by reason of the threaded engagement of the nut b' with the shaft, will have a rotary movement less than that of the driver a .
- 15 Therefore, it being assumed that the pump delivers at each stroke a quantity of gasoline less than the unit volume theoretically delivered, it will be seen that the pin b will have an angular movement less in a corresponding degree than that of the driver and furthermore that as the stroke of the pump and the movement of the driver a progresses, the pin will fall behind the motion of the driver. Through such devices as those to be described the movement of the pin is transmitted to the counter mechanism and the extent of the movement of the counter mechanism will therefore be governed in such manner that the movement of the counter mechanism will correspond to the effective operation of the pump. Furthermore, if it is necessary to increase the length of stroke of the pump in order to deliver the unit volume of the liquid, the extent of movement of the counter will not be increased correspondingly but the counter mechanism will be operated to the correct extent.
- 20 In the embodiment of the invention illustrated the angular movement of the pin b is transmitted to the counter mechanism by the devices now to be described. Mounted loosely on the shaft c' is a sleeve d which has longitudinal fingers d' in engagement with longitudinal slots b^2 of the nut b' , so that the sleeve d receives the same angular movement as the nut b' while the longitudinal movement of the nut is not interfered with. The sleeve d carries a pinion d^2 in engagement with the gears d^3, d^4 of an ordinary train of differential reducing gears through which movement is imparted to a gear d^5 . The latter, through a suitable clutch e , preferably a ball clutch, as shown 25 in detail in Figure 7, and a sleeve f , drives

the first number wheel g of the counter or register, the successive number wheels being driven in the usual manner. A ball clutch detent h , similar in construction to the driving clutch e , is provided for the purpose of preventing backward movement of the sleeve f and first number wheel in the rotary oscillations of the driving mechanism.

To effect the shifting of the pin from one notch to another of the driver a the counter is removed, together with the transmitting devices, and the pin b is shifted so that it will engage the proper slot of the driver. The counter is then replaced in position.

It will be observed that compensation proportional to the extent of movement of the driver, that is, proportional to the length of stroke of the pump, is accomplished by imparting to the pin or driven member of the compensating devices a helical motion, which in turn is accomplished by moving the pin longitudinally with respect to the coacting slot.

The mode of operation of the compensating devices described is substantially the same as that of the devices described in the application above mentioned and it will be seen that the lost motion or backlash which is an inherent possibility in the construction described in said application, is entirely obviated by the formation of the driving slots with the sides of each in parallelism.

I claim as my invention:

1. The combination of a counting mechanism for a pump, a driver therefor in operative relation with the pump and having a slot with its sides inclined in parallelism, and a driven member in operative relation with the counting mechanism and adapted for engagement with said slot.

2. The combination of a counting mechanism for a pump, a driver therefor in operative relation with the pump and having a series of differently inclined, parallel sided slots, and a driven member adapted for engagement with one or another of the slots of the driver and in operative relation with the counting mechanism.

3. The combination of a counting mechanism for a pump, a cup-like driver having in its peripheral wall a slot with its sides inclined in parallelism, a screw threaded member in axial alinement with the driver, a nut mounted on the screw threaded member and having a pin for engagement with the slot of the driver to be rotated thereby and to move longitudinally with respect thereto, and means for transmitting the rotary movement of the nut to the counting mechanism.

This specification signed this 21 day of February A. D. 1924.

CURTIS HUSSEY VEEDER.
